SWING LINE

Claude F. Tears, Warren, Pa., assignor to The Petroleum Processes Corporation, Wichita, Kans., a corporation of Kansas

Original application July 16, 1935, Serial No. 31,567. Divided and this application July 1, 1936, Serial No. 88,356

8 Claims. (Cl. 210—51)

This invention relates particularly to improvements in oil refining and is a division of copending Patent 2,049,277 of July 28, 1936.

In the art of separating solids and/or semi-solids from liquids by settling, or separating immiscible liquids by settling, it is highly desirable to determine the exact line of demarcation between the settled layer and the liquid or solution above it, so that the upper layer may be fully removed unmixed with the separated or settled layer.

In refining oils by settling from solutions of oil in normally gaseous liquefied hydrocarbons, the problem is complicated by the fact that the solvent being normally gaseous, must be held under pressure to keep it in the liquid state at temperatures above its normal boiling point.

The above mentioned Tears patent application covers a dewaxing and partial decolorizing process for lubricating oils involving separation of solid or semi-solid wax and solid or semi-solid color constituents from oil solutions in normally gaseous liquefied hydrocarbons by cold settling under pressure. The earlier Tears Patent 2,000,427 covers a process for the manufacture of high melting point wax by cold settling under pressure. In both processes, it is essential to determine as near as possible the location of the waxy layer in a closed tank under pressure and to remove the supernatant oily layer as close as possible to the waxy layer. The swing line construction of the present invention accomplishes these purposes.

The objects of the invention, as will appear from the foregoing are to provide practical and efficient means and method for accurately determining the different levels in a pressure settling vessel and for effecting the removal of the selected layer or layers.

These broad objects and others of a more specific nature are attained in this invention by the novel method of operation, features of construction, combinations and relations of parts, as hereinafter described, illustrated in the accompanying drawing and broadly covered in the claims.

The drawing accompanying and forming part of the specification shows by way of illustration a typical embodiment of the invention, it being realized that the structure may be modified in various ways all within the true intent and broad scope of the invention.

Fig. 1 is a broken side elevation, partly in section showing the invention applied to a chilling and settling tank.

Fig. 2 is a broken end elevation of the same.

Fig. 3 is a broken perspective view of the off-take and sampling spout at the end of the swing line.

The invention is illustrated in its application to the process of dewaxing and partially decolorizing lubricating oil disclosed in the patent application Ser. No. 31,567. The operation of that process involves the use of horizontal closed pressure tanks, such as indicated at 14. These are charged with a solution of oil in a normally gaseous liquefied hydrocarbon, such as propane, under pressure and the solution is chilled by evaporation of a portion of this solvent. The chilled solution is then permitted to settle under a superimposed pressure in excess of the normal vapor pressure of the solvent at the temperature of the chilled solution. The wax and color constituents settle from the chilled mixture and for proper operation of the process, it is essential to locate the top of the waxy layer and to follow it down until a time is reached when it ceases to drop further and which then indicates that settling is complete. It is then essential to withdraw the oil solution above the waxy layer down to a level as close as possible to the waxy layer and to accomplish this without removing any of the waxy layer. Failure to remove all the oily layer results in a loss of oil yield, while removal of part of the waxy layer with the oily layer results in a finished oil of too high color and too high pour test.

The adjustable swing line, here disclosed, carrying with it a sample line, provides practical and efficient means for quickly and accurately determining the level of separation between the oil and the waxy layers and the means for withdrawing the oil down to the waxy layer.

In the illustration, the swing line is shown as a horizontally extending pipe 68, rotatably mounted in a pressure stuffing box 69, substantially at the center of the end head of the tank and having an angled inner end portion 68', terminating in a take-off spout 70, and its outer end rotatably coupled at 71, to the stationary take-off line 34.

The sample line is indicated at 72, carried by or incorporated in the swing line and as having a valved discharge at 73, at the outer end, outside the tank.

The off-take spout 70 is shown in Fig. 3 as thinned down toward a plane substantially radial to the axis of rotation of the swing line to provide a narrow inlet, which will be substantially parallel with all different levels of liquid, enabling a more or less fine discrimination in all liquid level adjustments. This thinned spout is

illustrated as widened along the axis parallel to the axis of rotation, to give it the full capacity of the pipe. The sample line is indicated as terminating centrally of the mouth of the spout, so as to take an accurate sample right at the center of the inlet to the swing line.

5 A hand lever or levers such as indicated at 74, 74', may be provided on the outer portion of the swing line and suitable securing means may be provided such as the screw clamp 75, cooperable with the quadrant 76. The handle or handles 74, 74', serve both as means for adjusting and securing the swing line and in conjunction with the quadrant, or the tank itself, as indicators for 10 showing the position of the swing line within the tank. The quadrant, if desired, may be laid off in suitable indications of angle, height, volume or other values. The lower lever handle 74' is shown as extending in the same direction and 15 terminating in line with the inlet mouth of the swing line within the tank, so as to provide at the outside of the tank an actual visual counterpart of the swinging inlet within the tank.

The swing line is shown as equipped with valve 25 71, the stationary draw-off line 34, with valve 78, and the sample line with valve 73' by which these lines may be properly controlled.

With the construction and arrangement shown, the character of the material at any level in the 30 tank can be quickly determined by withdrawing a sample after the swing line has been set at such level. When a suitable point of withdrawal has been determined, as by observation of samples, the swing line may be definitely secured as by the 35 clamp 75, and the contents of the tank above that level removed through line 34, after opening valves 71 and 78.

In the dewaxing and partial decolorizing process referred to, after the settling tank has been 40 "pressured off" for about one hour, the swing line is set at about the middle of the tank and a small sample taken by the sample line. Usually at this time, the waxy layer has settled below the center of the tank. If it has settled below the 45 first setting of the swing line, the sample will be a clear bright solution. If it has not settled below this setting, the sample will be a dark waxy mixture. As the first setting near the central level of the tank will usually show the wax layer has settled below that point, the sample line 73' 50 may be left partly open and the swing line be slowly lowered until the sample stream changes from the clear bright solution to the dark waxy stream. The swing line may then be set at this 55 latter position representing the top of the waxy layer at that time. In the same manner, the location of the top of the waxy layer may be determined, say at 15 minute intervals. The location of the top of the waxy layer may thus be followed 60 down through the tank during the whole settling period. When the top of the waxy layer has failed to drop further for two consecutive 15 minute intervals, the settling may be considered as finished and complete. The swing line may 65 then be clamped in position and the oily layer above the location of the swing line inlet be forced or pumped out through line 34, with valves 71 and 78 open.

The invention enables the exact locating of 70 the top of the waxy layer, so much so that a variation of $\frac{1}{8}$ " in vertical location of the swing line inlet will show a distinct separation between the oily and waxy layers.

While of particular value for the settling operations disclosed, it will be understood that the

invention may be employed for various other settling operations, especially those involving removal of a liquid layer from above settled solids or semi-solids or from other immiscible liquids heavier than the top layer or layers.

5 By mounting the rotatable swing line horizontally and substantially at the center of the tank and by arranging the same for a substantially complete rotation, the tank contents may be taken off from any level and from any portion of the tank. This is so because of the fact that the inlet mouth of the swing line can be made to sweep the entire peripheral portion of the tank.

10 What is claimed is:

1. In combination with a closed horizontally extending pressure settling tank, a pressure stuffing box substantially centrally disposed in the end of said tank, a horizontally extending swing pipe entered in said tank and rotatable in said 15 pressure stuffing box, said swing pipe having an angularly projecting extension within the tank and terminating in an inlet mouth, a stationary draw-off pipe outside the tank, a swivel coupling between said draw-off pipe and the horizontal 20 portion of the swing pipe, means for rotating said horizontal portion of the swing pipe to locate the inlet mouth at different levels in the tank, valve means for controlling flow through the 25 swing pipe and a valved sample line carried by 30 and adjustable with said swing pipe and having an inlet at the mouth of the swing pipe and a valved outlet outside the tank.

2. In combination with a pressure settling chamber, a swing pipe rotatably entered in said settling chamber and terminating in a withdrawal spout inside said chamber and a sample line carried by said swing pipe having an inlet substantially at the mouth of said withdrawal spout and a valved discharge outside the chamber and independent of said swing pipe.

3. In combination with a pressure settling chamber, a swing line rotatably mounted and having a withdrawal spout within the chamber and a handle for rotating said swing line outside the 45 chamber, said handle projecting angularly from the center of rotation of said swing line, a sector over which said handle operates and clamp means between said handle and sector for securing said handle in various angular positions with respect 50 to said sector.

4. In combination, a horizontally extending rotatably supported swing pipe, having an angular extension terminating in an inlet mouth and a sample line carried by said angular extension 55 of said horizontally extending rotatably supported swing pipe and having an inlet at the mouth of said swing pipe.

5. In combination with a tank, a horizontally journalled withdrawal pipe having an angular extension terminating in an inlet mouth within the tank, a smaller sample line extending from said inlet mouth through said withdrawal pipe beyond the supporting bearing for the latter and a valved discharge outlet for the sample line opening through the side of the rotatably supported withdrawal pipe at a point beyond the bearing for the pipe and provided at said extended point with a controllable sample discharging outlet.

6. The herein disclosed method of settling and 70 decanting which comprises combining a small sample line with a movable off-take pipe so that said sample line will move with and be positioned by said off-take pipe, gradually lowering said pipe in the material being settled and taking samples 75

through said sample line at each stage of lowering until a point is reached where the samples so taken indicate that settling has been sufficiently completed and then securing said off-take pipe and withdrawing the material through the off-take pipe at such level.

7. The herein disclosed method of settling materials in a closed pressure vessel and decanting the settled material therefrom, which comprises combining a sample line with an off-take pipe by mounting the sample line on the off-take pipe and movably supporting the off-take pipe within the pressure vessel so that said off-take and sample line may be simultaneously shifted to different levels of take-off in said tank, gradually lowering the combined off-take and sample line through the material being settled and withdrawing samples through said sample line at different levels and then after samples so taken indicate that settling is completed, leaving the off-take pipe at such level and withdrawing the settled

material through said off-take pipe from such level.

8. In combination with a tank, a substantially horizontal bearing carried thereby, a swing pipe having a substantially horizontal portion journaled in said bearing and an angularly projecting portion within the tank and terminating in an inlet mouth, a stationary pipe in line with the substantially horizontally journaled portion of said swing pipe, a swivel coupling between said stationary pipe and said substantially horizontal portion of said swing pipe, a sampling tube carried by said swing pipe having an inlet in the region of the inlet mouth of said swing pipe, said sampling tube extending through the substantially horizontally journaled portion of said swing pipe and having an outlet between said horizontal bearing and the swivel coupling and valve means outside the tank for independently controlling said sampling tube and said swing pipe.
